United States Patent Office.

ALMA BEDFORD, OF COLDWATER, MICHIGAN.

Design No. 3,687, dated October 5, 1869.

DESIGN FOR A BUCKLE.

The Schedule referred to in these Letters Patent and making part of the same.

To all whom it may concern:

Be it known that I, ALMA BEDFORD, of Coldwater, in the county of Branch, and State of Michigan, have invented certain new and useful Improvements in Harness-Buckles; and I do hereby declare that the following is a full, clear, and exact description thereof, reference being had to the accompanying drawings, making part of this specification, and to the letters of reference marked thereon, like letters indicating like parts, wherever they occur.

To enable others skilled in the art to construct and use my invention, I will proceed to describe it.

My invention relates to harness-buckles, and consists in forming or constructing them of a new and original shape or configuration, so as to produce a buckle of a new design.

In the drawings—

Figure 1 is a top plan view, and

Figure 2 is a longitudinal vertical section, on the x : x of fig. 1.

I construct my buckle A of a rim, a , with an imitation roller, c , on its front end, and an expanded and

curved rear end, d , a cross-bar, b , having a tongue, B , mounted thereon, all as clearly shown in both figures.

The sides of the rim a in front of the cross-bar b , I slightly curve and incline to each other, as clearly shown in fig. 1.

On the front end of the rim a I fashion an imitation-roller, c , on which the loose end of the tongue B rests.

The sides of the rim a , in the rear of the cross-bar b , commencing at the cross-bar, I curve upward, as shown in fig. 2, and form that part of the rim connecting its sides, and being in the rear and above the cross-bar, in the shape d , as clearly shown in fig. 2.

In this way I produce a buckle of a new and original shape, and highly ornamental as a design.

Having thus described my invention,

What I claim, is—

The shape or configuration as herein shown and described, as a design for a harness-buckle.

Witnesses:

ALMA BEDFORD.

H. B. MUNN,

P. T. DODGE.
